UNITED STATES PATENT OFFICE.

JOHN W. NASMITH, OF MANCHESTER, ENGLAND.

COMBING MACHINE.

Application filed April 9, 1921. Serial No. 460,142.

To all whom it may concern:

Be it known that I, JOHN WILLIAM NASMITH, a subject of the King of Great Britain, and resident of Leegate, Heaton Mersey, Manchester, England, have invented 5 certain new and useful Improvements in Combing Machines, of which the following is a specification.

In my United States Patent No. 1,367,076 granted to me there is described a method of feed for combing machines in which the feed roller is pushed along the nipper plate without turning to make the feed, or in other words it slides along the plate, being prevented from turning by a ratchet and pawl. To regain its initial position in readiness for the next feed movement, it is rolled backwards over the material during the backward swing of the nipper. In order to 10 adjust the amount of feed and the position of the roller on the plate, each head of the six with which combers are usually built, had to be adjusted separately. The object 15 of the present invention is to connect all the six feed rollers in such a manner that the amount of feed and the position of the feed rollers on the nipper plate can be altered and adjusted simultaneously by a single screw affecting all six rollers.

In order that the invention may be clearly understood I append a sheet of drawings in which the invention is shown applied to a 20 comber constructed according to my United States Patent No. 1,369,532 but it will be understood that it may be applied equally well to any other combing machine in which the feed roller is carried on and swings with the nipper.

Fig. 1 is a section through the middle of 25 a head showing the nipper and feed roller when in their nearest position to the detaching roller D and showing only such parts as are necessary.

Fig. 2 is a similar section showing the 30 necessary parts in their opposite extreme position whilst the cylinder C is combing.

The feed roller F rests on the nipper plate P² attached to the bridge B cast with the 35 nipper cheeks N², the whole swinging on the adjustable nipper pivot N and receiving its oscillating motion from the shaft W through the rod 17 and pin 16. The roller bearing 30 can be moved along and set in any 40 position on the rod 31 which is pivoted at 32 on the lower arm of the right angled lever L hinged loosely on the pin 16. The other

arm of the lever L carries a pin 33 on which pivots the connecting rod 34 whose other end is hinged to the extremity of the lever 35 keyed on the shaft T³, which extends 60 throughout the length of the machine and may rock freely in bearings in the framing of the machine. Keyed on the shaft T³ is the lever 36 having turned on one side of it a boss on which the plate 37 is adjustably 65 mounted so that the lever and plate have a common center. The plate 37 has a projection 38 which comes against a block 39 fixed on the rod 40 which extends throughout the length of the machine. A second projection 70 41 on the plate 37 carries a set screw S so that the oscillation of the plate and the shaft T³ is adjustably limited by the gap between the end of the set screw and the projection 38. The width of this gap determines the 75 extent of the movement (that is the amount of feed) of the roller F on the plate P² as will be further described below. The plate 37 has formed in it a circular slot 42 so that it can be fixed by the screw 43 in various 80 positions in relation to the lever 36. The alteration of this relation alters correspondingly the position in which the feed roller F operates on the plate P². For instance for long fibre it might have to be set back on the 85 plate so as to occupy the position indicated by the dotted lines in Fig. 2. Each roller can be set individually by positioning the bearing 30 on the rod 31 and being all set in line and the same distance from the nipper 90 point, they can be all altered simultaneously by displacing lever 36 in relation to plate 95 37 as described.

The roller F is pressed against the plate P² by the spring 44 acting through the lever 95 45 pivoted at 46 and one end of which presses on the top of the roller bearing 30 and this frictional contact prevents the displacement of the roller on the plate except when it is forcibly displaced as will now be 100 described.

In Fig. 1 the nipper is shown in its most 105 forward position the feed being just completed. It then swings backwards on the pivot N to the position shown in Fig. 2 and owing to the frictional pressure on the feed 110 roller bearing, just mentioned, the lever L on the pin 16 is carried with it and through the rod 34 and lever 35 rocks the shaft T³ carrying with it the lever 36 and plate 37 until the projection 38 contacts with the fixed stop provided by the block 39 where-

upon the lever L can no longer accompany its pivot 16 which continues its course causing the lever L to turn on its pivot and draw the roller F (through the rod 31) backwards 5 on the plate P². When the nipper swings in the opposite direction, the whole system moves together until the set screw S contacts with the stop block 39 when the lever L is again arrested and the continued movement of the pivot 16 causes L again to turn thereon and pushes the roller F along the plate, without turning as previously described, and thus make the feed. By widening the gap between the set screw S and the projection 38 the feed is shortened and vice versa. If whilst the parts are in the position of Fig. 1 the screw 43 be loosened and the plate 37 held whilst the lever 36 is moved to a different position in relation thereto 15 the shaft T³ and its connections will move the roller F to a different position on the plate P² the displacement being limited by the extent of slot 42.

Claims.

25 1. In a combing-machine of the character described, a nipper and feed roller mounted to swing on a common axis, a shaft and connections between the swinging nipper and roller and said shaft to transmit rocking movement to the shaft, and adjustable de-

vices connected with said shaft for variably limiting its rocking movements.

2. In a multiple-head combing-machine of the character described, the combination with the swinging nipper and feed roller elements thereof, the rollers being independently adjustable relative to the nipper, of a rock shaft, connections for actuating the rock shaft from the nipper, and adjustable devices connected with said shaft for variably limiting its rocking movements.

3. In a combing-machine of the character described, the combination with the swinging-nipper P², of the lever L pivoted to said nipper, the rod 31 connected to one end of 45 said lever, the feed roller F adjustable on said rod, the spring-actuated friction lever 45 for pressing the feed roller against the nipper, the rock shaft T³ having two arms, the link 34 connecting one of said arms with the said lever L which is pivoted to the nipper, a fixed stop, the slotted plate 37 mounted on the shaft T³, and having projection 38 and set screw S at opposite sides of said stop, and means for adjustably fixing the 55 position of the slotted plate 37 relatively to the other of said two arms of the rock shaft.

In testimony whereof I have affixed my signature.

J. W. NASMITH.
